UNITED STATES PATENT OFFICE.

THOMAS H. SEELY, OF MALDEN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

THREAD GRIPPING AND CUTTING DEVICE FOR SHOE-SEWING MACHINES.

1,396,066.

Specification of Letters Patent.

Patented Nov. 8, 1921.

Application filed November 2, 1916. Serial No. 129,093.

To all whom it may concern:

Be it known that I, THOMAS H. SEELY, a citizen of the United States, residing at Malden, in the county of Middlesex and State of Massachusetts, have invented certain new and useful Improvements in Thread Gripping and Cutting Devices for Shoe-Sewing Machines; and I do hereby declare the following to be a full, clear, and exact 10 description of the invention, such as will enable others skilled in the art to which it appertains to make and use the same.

This invention relates to shoe sewing machines, and more particularly to devices for severing the thread between the work and supply at the completion of the sewing of a seam, and for holding the free end of the thread projecting from the thread handling devices during the first part of the formation 20 of a new seam.

The objects of the invention are to improve the construction and mode of operation of thread cutting and holding devices of this character, and to produce a thread holding device which may be easily adjusted for different sizes of thread, and in which the tension or friction exerted by the thread holding device on the thread may be readily regulated to insure the proper formation of 30 the first few stitches.

With these objects in view, the features of the invention consist in certain improved constructions and new combinations of parts hereafter described and pointed out in the 35 claims, the advantages of which will be readily understood by those skilled in the art.

The features of the invention will be readily understood from the accompanying drawing illustrating a machine embodying 40 the invention in its preferred form, and the following detailed description of the construction therein shown.

In the drawings, Figure 1 is a view in side elevation of a portion of a curved hook 45 needle inseam shoe sewing machine embodying the invention; Fig. 2 is a view of the thread cutting and holding devices of the machine, detached from the machine, looking in the direction of the arrow *a*, Fig. 1; Fig. 3 is a view of the thread cutting and holding devices detached from the machine, looking in the direction of the arrow *b*, Fig. 1; and Fig. 4 is a sectional view taken substantially on the line 4—4 of Fig. 3.

The machine embodying the invention as 55 illustrated in the drawing is a shoe sewing machine of the class employing a curved hook needle and devices coöperating therewith to form a chain-stitch seam, and is designed particularly for sewing inseams of 60 welted and turned shoes. The machine is provided with a curved hook needle 2, a thread finger 4, a looper 6, and a channel guide 8, all having the same construction, arrangement and mode of operation as the 65 corresponding parts of the machine illustrated and described in applicant's prior application, Serial No. 815,127, filed January 29th, 1914.

The thread cutting and holding devices 70 illustrated in the drawing comprise a block 10 having an arm 12 extending therefrom and secured to the shank of the looper 6 by means of a screw 17 passed through an opening 16 in the end of the arm and threaded 75 into the looper. Mounted on the block 10 so as to embrace the block is a U-shaped spring plate 20 having substantially parallel arms 22 and 24. The block 10 and the arm 22 of the spring plate are respectively 80 formed with opposed thread holding jaws 26 and 28 adapted to grip and hold frictionally the end of the thread when the thread is placed between the jaws. The opposed thread holding jaws are oppositely curved 85 to form a substantially V-shaped entrance to the opening between the jaws to direct the thread into the contracted portion of the opening where it may be held by the jaws. The free end of the thread projecting from 90 the thread handling devices is inserted between the thread holding jaws before the starting of a seam. The jaw 26 holds the thread with a yielding pressure against the jaw 28, and as the seam is started, the thread 95 slips between the jaws under the pull exerted on the thread by the thread handling devices. The thread end is thus maintained under tension by the friction of the thread holding jaws on the thread during the formation of the first one or two stitches of a new seam, thereby insuring the proper formation of the stitches.

In sewing machines employed upon shoe work different sizes of thread are often employed in sewing different classes of work, and in accordance with one feature of the present invention means is provided for

adjusting the opening between the thread holding jaws to enable the proper tension to be exerted by the thread holding jaws on the thread whatever the size of the thread.

5 In the construction shown, an adjusting screw 30 is threaded into the block 10, and is arranged to engage at its outer end the inner side of the arm 22 of the spring plate 20. To enable the screw 30 to be readily 10 adjusted, the outer end of the screw is formed with a screw driver slot, and the arm 22 of the spring plate 20 is formed with an opening 32 opposite the screw through which a small screw driver may be inserted 15 to adjust the screw. The position of the adjusting screw 30 determines the position of the jaw 26 of the thread holding device with relation to the jaw 28 or the width of the opening between the thread holding 20 jaws. By turning the screw 30 in a direction to unscrew it from the block 10, the arm 22 of the spring plate is moved away from the block 10, thereby increasing the opening between the thread holding jaws, 25 and upon turning the adjusting screw in a direction to screw it into the block 10, the arm 22 moves toward the block 10, thereby diminishing the opening between the thread holding jaws.

30 As stated above, in the operation of the thread holding devices, the thread is drawn through the jaws of the thread holding devices during the formation of the first few stitches, the friction exerted by the thread holding jaws on the thread furnishing the tension required for the proper formation of the stitches. In accordance with another feature of the present invention, means is provided for adjusting the pressure exerted 35 by the thread holding jaws on the thread so that the action of the jaws may be regulated to furnish just the tension required to form and tighten the first few stitches in a certain and reliable manner. In the 40 present construction a second adjusting screw 37 is threaded into the block 10 and is arranged to engage at its inner end the inner side of the arm 24 of the spring plate 20. The outer or head end of the adjusting 45 screw 37 projects through a second opening 36 in the arm 22 of the spring plate 20 so that a screw driver may be readily inserted in the screw driver slot formed in the outer end of the screw to adjust the same. By 50 turning the adjusting screw 37 in a direction to screw it into the block 10, the arm 24 of the spring plate is forced away from the block 10, thereby increasing the tension of the spring plate. This adjustment of the 55 screw will cause the thread holding jaws to exert a greater pressure upon the thread than before. Upon turning the adjusting screw 37 in a direction to unscrew it from the block 10, the arm 24 of the spring plate 60 65 will move toward the block 10 thereby less-

ening the tension of the spring plate. This will result in diminishing the pressure exerted by the thread holding jaws upon the thread.

The adjusting screw 37 also acts as a stop 70 to limit the extent to which the thread may be inserted between the thread holding jaws.

It is to be noted that with the adjusting devices described above, the opening between the thread holding jaws may be adjusted 75 without changing the pressure exerted by the thread holding jaws on the thread, and that the pressure exerted by the thread holding jaws on the thread may be adjusted without changing the opening between the jaws. 80

The thread cutting device for severing the thread between the shoe and the supply consists of a cutting blade 38 formed upon the arm 22 of the spring plate and arranged 85 at an angle to the plane of said arm, as shown in Figs. 1 and 2. The edge of the cutting blade is directed away from the opening between the thread holding jaws 26 and 28, and extends substantially parallel 90 with the median plane of the opening. With the thread holding devices mounted upon the looper arm, as shown in Fig. 1, the thread cutting blade extends forwardly and upwardly from the thread holding devices 95 so as to enable the thread to be severed by the operator after having been inserted in the thread holding jaws by an easy and convenient movement of the shoe.

With this construction of the thread cutting and holding devices, after the shoe has been manipulated to disengage the channel guide from the channel, the shoe is moved upwardly and forwardly to locate the thread in position for insertion between the thread holding jaws 26 and 28, is then moved to the right to insert the thread between the jaws and to carry the thread over the thread cutting blade 38, as shown in Fig. 1, and is then moved downwardly to draw the thread taut across the edge of the blade to sever the thread. 100

Having explained the nature and object of the invention, and having specifically described a machine embodying the invention 115 in its preferred form, what is claimed is:

1. A shoe sewing machine, having, in combination, stitch forming devices including a hook needle and a looper, a thread holding device having opposed thread holding jaws yieldingly pressed toward each other, and means for adjusting independently the opening between the jaws for different sizes of thread and the pressure exerted by the jaws on the thread. 120

2. A shoe sewing machine, having, in combination, stitch forming devices including a hook needle and a looper, a thread holding device having opposed thread holding jaws yieldingly pressed toward each other, and 125 130

- means for relatively adjusting the jaws toward and from each other to vary the width of the opening between the jaws for different sizes of thread without changing the pressure 5 exerted by the jaws on the thread.
3. A shoe sewing machine having, in combination, stitch forming devices including a hook needle and a looper, a thread holding device having opposed thread holding jaws 10 yieldingly pressed toward each other, and adjustable means for limiting the relative movement of said jaws toward each other.
4. A shoe sewing machine, having, in combination, stitch forming mechanism including a hook needle and a looper, a block having a thread holding jaw formed thereon, a U-shaped spring plate embracing said block and having at the end of one arm a thread holding jaw arranged in opposed 15 relation to the first jaw, and an adjusting screw threaded into the block and engaging the other arm of the spring plate to adjust the pressure of the jaws on the thread.
5. A shoe sewing machine, having, in combination, stitch forming mechanism including a hook needle and a looper, a block having a thread holding jaw formed thereon, a U-shaped spring plate embracing said block and having at the end of one arm a thread holding jaw arranged in opposed 20 relation to the first jaw, and an adjusting screw threaded into the block and engaging said arm to adjust the opening between the jaws for different sizes of thread.
- 35 6. A shoe sewing machine, having, in combination, stitch forming mechanism including a hook needle and a looper, a block having a thread holding jaw formed thereon, a U-shaped spring plate embracing said 25 block and having at the end of one arm a thread holding jaw arranged in opposed relation to the first jaw, an adjusting screw threaded into the block and engaging said arm to adjust the opening between the jaws for different sizes of thread.
- 40 7. A shoe sewing machine, having, in combination, stitch forming mechanism including a hook needle and a looper, a block having a thread holding jaw formed thereon, a U-shaped spring plate embracing said 30 block and having at the end of one arm a thread holding jaw arranged in opposed relation to the first jaw, and an adjusting screw threaded into the block and engaging said arm to adjust the opening between the jaws for different sizes of thread.
- 45 8. A shoe sewing machine, having, in combination, stitch forming devices including a hook needle and a looper, a thread holding device having opposed thread holding jaws 35 yieldingly pressed toward each other, 40 adjustable means for limiting the relative movement of said jaws toward each other, and means for adjusting the force with which said jaws are pressed toward each other.
9. A shoe sewing machine having, in combination, stitch forming devices including a hook needle and a looper, a thread holding device having opposed thread holding jaws yieldingly pressed toward each other, 45 adjustable means for limiting the relative movement of said jaws toward each other, and means for adjusting the force with which said jaws are pressed toward each other.
10. A shoe sewing machine having, in combination, stitch forming devices including a hook needle and a looper, a thread holding device having opposed thread holding jaws, a spring plate upon which one of said jaws is formed, and an adjusting screw 50 engaging said spring plate to limit adjustably the movement of the jaw formed thereon toward the other jaw, and an adjusting screw engaging said spring plate to adjust the pressure with which the jaw formed thereon is pressed toward the other jaw.
11. A shoe sewing machine, having, in combination, stitch forming mechanism including a hook needle and a looper, a block having a thread holding jaw formed thereon, a U-shaped spring plate embracing said 55 block and having at the end of one arm a thread holding jaw arranged in opposed relation to the first jaw, and means for relatively adjusting the arms of the spring plate.

THOMAS H. SEELY.
